UNITED STATES PATENT OFFICE.

GEORGE C. HUNTER, OF CLEVELAND, OHIO.

MACHINE FOR SHARPENING SAWS.

1,272,339.

Specification of Letters Patent.

Patented July 9, 1918.

Application filed December 28, 1917. Serial No. 209,217.

To all whom it may concern:

Be it known that I, GEORGE C. HUNTER, citizen of the United States, residing at Cleveland, in the county of Cuyahoga and

5 State of Ohio, have invented certain new and useful Improvements in Machines for Sharpening Saws, of which the following is a specification.

This invention relates to a machine for 10 sharpening saws, and has for its object to provide an improved machine adapted for sharpening saws of various kinds, such as band saws, hack saws and circular saws. Machines have heretofore been provided for 15 sharpening single types of saws, but by the present invention saws of various types may be sharpened.

The machine is of that type in which the saw is fed along, or rotated, intermittently, 20 to present the successive teeth to the action of a grinding wheel or disk, this disk being mounted on a frame which is raised and lowered intermittently, in time with the movement of the saw.

25 A further object of the invention is to provide improved means for raising and lowering the grinding disk, and also for adjusting the position or angle thereof, with respect to the work.

30 A further object of the invention is to provide improved means for varying the saw feed.

A further object of the invention is to 35 provide improved means of stopping the up and down movement of the sharpening wheel without throwing off the power.

A further object of the invention is to 40 provide improved means for supporting various types of saws in position for the sharpening operation.

Other features of novelty will be apparent from the following description and the accompanying drawings.

In the drawings—

45 Figure 1 is a perspective view showing the machine arranged for sharpening a circular saw.

Fig. 2 is a similar view showing the arrangement for sharpening a hack or band saw.

50 Fig. 3 is a detail in perspective of the cam mechanism for lifting the grinding disk.

Fig. 4 is a detail in side elevation showing the lifting mechanism out of action.

Fig. 4^a is a detail of a universal joint.

Fig. 5 is a perspective view of the machine as seen from the rear.

Fig. 6 is a detail of a holder for a band or hack saw.

60 Fig. 7 is a detail in section of part of the lifting devices.

Referring specifically to the drawings, F indicates a frame of suitable construction to support the parts to be hereinafter described. 1 is a power shaft which extends from the rear of the machine under the table or top thereof and carries fast and loose pulleys 2 for the application of a driving belt. The shaft also carries a pulley 60 70

for driving the emery wheel spindle to be hereinafter described. Upon the inner end of the shaft 1 is a worm 3 which meshes with a worm gear 4 mounted on a cross shaft 5 supported in suitable bearings under the 75 table of the frame. This shaft 5 carries a cam 6 which acts on a roller 7^a by a lifting arm 7 which is pivoted at 8 to the frame.

This arm, by a universal joint connection 10, acts to raise and lower a screw rod 9, the 80 threaded part 13 of which extends through a long split nut at 12^a having a socket 12^b which receives the round head 12^c of a pin “gate” 11. The ball and socket joint permits universal movement. The nut may be 85 held at adjustment on the rod by a clamp screw 12. The slide 11 is movable up and down in a slide way or vertical guide bracket 14. The guide way 14 is integral with a rearwardly projecting ring or cuff 90 14^a which is held in an outer rim 14^b, which stands on the frame and is split as indicated at 14^c, with a clamp screw 14^d to tighten the rim on the cuff. By loosening the clamp, the guide way 14 and cuff 14^a, 95 as a whole, may be turned to various angles on either side of the vertical, and this adjustment fixes the set or angle of the grinding disk with respect to the work, since the grinding disk spindle is carried by the slide 100 11 which is supported in the guide 14. The slide 11 has bearing brackets 15^a projecting forwardly therefrom and supporting the spindle 15 of the grinding wheel or disk 16.

This spindle has a pulley 17 between the 105 brackets which is driven by a belt 61 from the pulley 60, the belt passing through openings in the frames 11 and 14 and over guide pulleys 62 at the rear of the guide ways 14, the arbors of these pulleys being 110 adjustably supported by bracket 63 standing on the frame at the back thereof.

By adjusting the screw rod 9 the grinding wheel carrier may be raised or lowered to vary the position of the wheel with respect to the work, and by the rotation of the cam 6, the arm 7 is lifted and dropped and the emery wheel is intermittently raised and lowered in time with the saw feed.

Mounted on the end of the cross-shaft 5 is a face cam 18 which acts against a roller 19 carried by a dependent arm 20 which swings on a rock shaft 21 extending from front to rear at one end of the machine, the shaft being supported by the suitable bearing bracket on the end of the frame. Also 15 loosely mounted on this shaft is an arm 22, projecting upwardly and carrying, by means of a head 22^a, a pair of feeding fingers or pawls 23 which project in position to engage the teeth of the saw just in advance of 20 the grinding disk. 28 is an arm fast on the rock shaft 21, and depending behind arm 20 and provided with a set screw 27 the end of which rests against the back of the arm 20. A spring 29 connects the arms 25 28 and 20. 25 is an arm fast on the rock shaft 21 and offset behind the arm 22, to which it is connected by a spring 26, and a set screw 24 carried by the arm 25 abuts against the arm 22. The head 22^a is also 30 provided with a set screw 24^a, for adjustment of the pawls 23 and with respect to the arm 22.

By means of the arms 20, 28, 22, and 25, and the set screws 24 and 27, motion imparted to the arm 20 by the cam 18 is transmitted to the feeding pawls 23 and the relative amount of throw may be adjusted according to the size or spacing of the teeth of the saw being sharpened, so as to advance 40 the saw a proper distance at each operation to register the grinding disk therewith. Obviously the cams 6 and 18 will be so timed that the feed of the saw will be produced while the grinding disk is raised from the 45 work.

For work on a hack or band saw, as shown in Fig. 2, I provide a bracket 31 which is bolted as shown at 44 to a slide 30 which is movable up and down in a slide way 30^a at 50 the front of the machine and is adjustably supported by a screw 34 operated through bevel gears 35 and 36 by a handle 37. The bracket 31 has a steel plate 32 at the top upon the upper edge of which the saw rests, 55 and at each end of the plate the bracket has a slotted lug 33 through which the saw passes. When this bracket is used the steel plate projects upwardly between a front guide bar 38 and a rear guide bar 38^a extending across the front of the machine under the grinding head. The front bar 38 is supported by a pair of spring arms 39 each of which is fastened to an angle plate 40 pivoted at 41 to the ends of the frame, and 60 held by removable pins 42. By removing 65

the pins, the bar 34 may be swung out and down forwardly to release the saw. 43 is a knob on the bar to operate it. The front and rear bars 38 and 38^a, the steel plate 32, and the slotted lugs 33, are all lined to form 70 a guide way through which the saw is fed by the pawls as above described, and this arrangement is used for hack or band saws. By means of the handle 37 the bracket can be raised or lowered to properly position 75 saws of different widths.

For grinding circular saws, as shown in Fig. 1, the bracket 31 is removed by taking out the bolts 44. The circular saw C is mounted on an arbor 46 entered through the 80 slot in a hanger 45 depending from the bar 38, the arbor being fastened by a hand nut 47 to clamp the circular saw at the desired elevation to present its teeth to the grinding disk. In this position, by the feeding mechanism described, the circular saw will be turned to present the teeth in succession to the disk, the disk being raised or lowered by the cam 6 as before. In this construction, the saw will swing with the bar 38 when the 90 latter is let down by releasing the catch 42, and this permits the saw to be readily attached or detached. A detent 51 may also be provided to engage the saw teeth and prevent back slip thereof. This detent is pivoted at 52 and may be swung back out of action when desired, as shown in Fig. 2.

For stopping the operation of the "gate" a rod 49 is provided, mounted in a support in the frame and provided at its outer end 100 with a hand wheel 50 and at its inner end with a cam 48 located under the lifter 7, and by turning the handle, the lifter may be raised out of contact with the cam 6, as shown in Fig. 4, in which position the up 105 and down movement will cease and the saw may be inspected without stopping the main drive.

The universal joints at 10 and 12^c permit angular variation of the rod 9 incident to 110 the rise and fall of the "gate" in the angular guide ways, and the "ring" support for the guide 14 permits the angle or set of the grinding disk to be varied according to the kind of saw teeth being ground.

115 A belt shifter is shown at 53, operated by a handle 54.

I claim:

1. The combination with a saw sharpening machine of the type having a guide-way 120 for a straight saw and means to advance the saw along the same, of a removable plate forming part of said guide-way, and means to support a circular saw for rotation in the position occupied by said plate, upon removal thereof.

2. In a saw sharpening machine, a guide-way comprising two side bars, and a removable bottom plate adapted to support a straight saw between the side bars, and 130

- means to support a circular saw between the side bars, upon removal of the bottom plate.
3. In a saw sharpening machine, a guide-way comprising two side bars, one of which is pivoted to swing toward or from the other, and a bracket attached to the latter side bar and provided with means to clamp a circular saw thereto with its edge between the bars.
- 10 4. In a saw sharpening machine, a feed mechanism comprising a rock shaft having two arms loose thereon, two other arms fast on the rock shaft, an adjustable connection between each of the fixed arms and each of the loose arms respectively, cam means to vibrate one of the loose arms, and a saw feeding pawl carried by the other loose arm.
5. Means to support a grinding disk spindle for angular adjustment, comprising a fixed circular rim, a circular member fitting the rim and arranged to turn circumferentially thereon, and means to support the spindle in transverse position across said member, whereby adjustment of said member varies the inclination of the spindle.
6. In a saw sharpening machine, a guide-way comprising two side bars, and a vertically adjustable bracket provided with a bottom plate fitting edgewise between the side bars, to support a saw there between, the bracket also having slotted lugs at the ends of the side bars, with the slots in line with the guide-way between the bars.
- 35 7. In a saw sharpening machine, the combination with a grinding wheel spindle, of a sliding carrier therefor, an adjustable rod connected to the carrier, a lifter arm on which the rod rests, and means to vibrate the arm, said means including a cam operating against the arm, and means to lift the arm out of contact with the cam.
8. In a saw sharpening machine, the combination with a frame having upright guides, a carrier slidable up and down in said guides, a grinding wheel spindle supported on said carrier, means to drive the spindle, and means to reciprocate the carrier, said means including a lifter mounted on the frame, and a rod connected to the carrier and to the lifter, the connection to the carrier including an adjusting screw and the connection to the lifter including a universal joint.
9. In a saw sharpening machine, the combination of a fixed supporting circular rim, a guide having a circular cuff fitting said rim and adjustable angularly thereon, a carrier slidable on the guide, a rotary grinding disk mounted on the carrier, means to drive the disk, and means to reciprocate the carrier.
- 55 10. In a saw sharpening machine, the combination of an outer circular supporting rim, a guide having an annular part fitting in the rim and adjustable therein to various angles with respect to the guide, a grinding disk spindle supported on the front of the carrier frame, a driving belt for said spindle, passing from front to back through the carrier frame and the annular part of the guide, and means to reciprocate the carrier frame.
- 15 11. Means to support a grinding disk for angular adjustment, comprising a fixed vertical rim, an annular cuff fitting in said rim and provided with guides on one face thereof, the cuff being movable circumferentially for angular adjustment in the rim, a carrier slidable in said guides, and a spindle supporting the grinding disk and mounted on the face of said carrier.
- 20 12. Means to support a grinding disk spindle for angular adjustment, comprising two rings one of which is fixed and the other of which is adjustable circumferentially thereon to various angles, and means to support the spindle in transverse position upon the adjustable ring, whereby adjustment of the ring varies the inclination of the spindle.
- 25 13. The combination of a fixed ring, an adjustable ring mounted to turn circumferentially therein, a grinding disk spindle extending transversely across one side of the adjustable ring and supported thereon, and a driving belt extending through the rings from the opposite side thereof and engaging the spindle to drive the same.
- 30 In testimony whereof, I do affix my signature in presence of two witnesses.
- GEORGE C. HUNTER.
